(57) **CLAIM**

The ornamental design for a light emitting elongated tube base, as shown and described.

DESCRIPTION

FIG. 1 is a top perspective view of the design according to the invention.

FIG. 2 is a bottom perspective view of the design according to the invention.

FIG. 3 is a front view of the design according to the invention, a rear view being a mirror image thereof.

FIG. 4 is a left view of the design according to the invention, a right side view being a mirror image thereof.

FIG. 5 is a top plan view of the design according to the invention.

FIG. 6 is a bottom view of the design according to the invention; and,

FIG. 7 is a top perspective view of the design shown in use according to the invention.

The broken lines shown represent unclaimed portions of the design and environmental structure, and form no part of the claimed design. The broken away jagged lines indicate that the design is of non-specified length.
